UNITED STATES PATENT OFFICE.

JOHN PAULAUSKI, OF CHICAGO, ILLINOIS.

SAFETY DEVICE.

1,136,710.

Specification of Letters Patent. Patented Apr. 20, 1915.

Application filed September 14, 1914. Serial No. 861,592.

To all whom it may concern:

Be it known that I, JOHN PAULAUSKI, a citizen of the United States, residing at Chicago, in the county of Cook and State 5 of Illinois, have invented certain new and useful Improvements in Safety Devices, of which the following is a specification.

This invention relates to stops or safety devices for mine cars, the same being designed to prevent the running away of a car 10 on an inclined passage-way or gallery in the event of said car breaking loose from the train; and the invention has for its object to provide a simple and efficient device 15 of this kind.

With the herein stated object in view, the invention consists in a novel combination and arrangement of parts to be hereinafter described and claimed, reference being had 20 to the accompanying drawing, in which—

Figure 1 is a plan view of the invention, and Fig. 2 is a side elevation thereof.

Referring specifically to the drawing, 5 denotes a passage-way or gallery in a mine, 25 the same having a track 6 on which travel the trains of cars which transport the products of the mine. As shown in Fig. 2, the passage-way or gallery is inclined, in view of which provision is made for stopping a car if the same should break loose from the train; or to stop the entire train 30 if it should get beyond control and start to travel back down the incline.

The safety stop device comprises a buffer beam 7 having a reduced rear end 8 which is slidably mounted in an aperture in a rigid horizontal bracket arm 9 mounted on the wall of the passage-way 5 and projecting outward from said wall in the direction of 35 the track 6. Between the bracket arm and a shoulder on the buffer beam formed by the reduced end thereof, is interposed a coiled spring 10 which opposes the rearward or inward movement of said beam. The aperture in the bracket arm 9, through which the part 8 passes, is wide enough to allow the buffer beam to swing transversely of the track 6. A spring 11 between the buffer beam and the wall of the passage-way normally holds the former swung over toward 40 the track a sufficient distance so as to be in the path of the cars traveling on said track. A chain 12 connecting the buffer beam to the wall of the passage-way limits the outward swing 45 of the beam. The buffer beam is supported in horizontal position by a brace 50

bar 13 pivoted at 14 to the floor of the passage-way and loosely connected at its upper end to the beam near the outer end of the latter, a loose connection being necessary to permit the transverse swing of the beam and also its movement in the direction of its length. 60

As stated, the buffer beam 7 is normally in the path of the cars traveling on the track 65 6, and it is so mounted that when the cars are traveling up the incline, they push the beam back to clear the same, as shown dotted in Fig. 1. As soon as the cars pass, the buffer beam swings back to the full line 70 position. If, however, a car on the train should start to travel down the incline, the buffer beam at once acts as a barrier to stop the same. The impact of the car or the train against the buffer beam slides the same 75 rearward against the tension of the spring 10, and the latter therefore serves to cushion the movement of the beam.

A sufficient number of the hereinbefore described safety stop devices to afford complete protection will be mounted in the passage-way or gallery. 80

I claim:

1. A safety stop device for cars, comprising a buffer beam mounted to swing transversely of the line of travel of the car and to move in the direction of its length, yielding means opposing the last-mentioned movement of the beam in one direction, yielding means normally holding the beam 85 in the path of travel of the car, said means allowing the beam to swing inward when the car is traveling in one direction, and means for limiting the outward swing of the beam. 90

2. A safety stop device for cars, comprising a buffer beam, a bracket arm having an aperture through which the beam passes loosely, said beam being free to slide in the aperture and to swing therein, yielding means opposing the last-mentioned movement of the beam in one direction, and yielding means normally holding the beam in the path of travel of the car, said means allowing the beam to swing inward when the car 100 is traveling in one direction. 105

3. A safety stop device for cars, comprising a buffer beam mounted to swing transversely of the line of travel of the car and to move in the direction of its length, yielding means opposing the last-mentioned movement of the beam in one direction, 110

yielding means normally holding the beam in the path of travel of the car, said means allowing the beam to swing inward when the car is traveling in one direction, means 6 for limiting the outward swing of the beam, and a pivoted brace bar loosely connected to the beam.

In testimony whereof I affix my signature in presence of two witnesses.

JOHN PAULAUFSKI.
